CLAMP HANGER

Stanley J. Otis, Madison, Wis.

Application February 6, 1948, Serial No. 6,649

11 Claims. (Cl. 248—228)

1

The present invention relates to clamp hangers for securing to structural beams and the like any of a wide variety of building elements such as utility conduits, furring strips, and the like.

More particularly the invention provides an improved device adapted to be quickly and permanently attached to the lower portion of a floor joist for securing thereto any of the elements and appendages which are commonly mounted on or between such joists in the erection of buildings.

Among the objects of the invention are to provide an attaching device for the purpose indicated which will be extremely inexpensive to make and which will require no tool or fastening means to mount it in position.

Other objects are concerned with providing a device of the character indicated which can be quickly installed by inexperienced and unskilled persons and which will remain securely installed until it is intentionally removed.

A related purpose is to provide a hanger which will resist separation from the supporting joist or the like resulting from the load of the object which it supports, i. e., to provide a hanger which will tighten its grip on the joist or the like as the load or pull effected by the hung load increases.

A further object is to provide a clamping device of great versatility and adaptability which can be used to mount any of a wide variety of conduits and the like in any desired position and location relative to the supporting joists, i. e., below or above the bottom surfaces of the joists, and parallel to or transversely of them.

With the foregoing and other objects and advantages in view, some of which it is believed will be apparent to those skilled in the art from the accompanying drawings and the following description, an embodiment of the invention which has been tested and found to give entirely satisfactory service, and hence is at present preferred, is illustrated by the accompanying drawings, in which

Figure 1 is a perspective view of a precast concrete beam or joist with a clamp hanger as contemplated by the present invention affixed thereto;

Fig. 2 is an end elevational view of the lower portion of such a beam or joist showing one of the clamp hangers in an intermediate position in the operation of being mounted;

Fig. 3 is a perspective view of the tongue member of the hanger;

Fig. 4 is a perspective view of the fork member of the hanger;

2

Fig. 5 is an end elevational view of a joist showing a mounted hanger supporting a pipe in a position close to the under surface of the joist and extending parallel thereto;

Fig. 6 is a side elevational view of a joist showing a mounted hanger supporting a pipe in a position close to the under surface of the joist and extending transversely thereof;

Fig. 7 is an end elevational view of a joist showing a mounted hanger supporting a pipe spaced below the under surface of the joist and extending parallel thereto;

Fig. 8 is a side elevational view of a joist showing a mounted hanger supporting a pipe spaced below the under surface of the joist and extending transversely thereof;

Fig. 9 is an end elevational view of a pair of joists showing a pair of mounted hangers supporting a duct which extends longitudinally through the space between the joists;

Fig. 10 is an end elevational view of a pair of joists supporting a duct in the manner shown by Fig. 9, but at a higher elevation in the space between the joists;

Fig. 11 is a side elevational view of a joist showing a pair of mounted hangers supporting a duct extending transversely of the joist, immediately beneath it;

Fig. 12 is an end elevational view of a pair of joists showing a pair of mounted hangers supporting a duct which extends parallel to the joists, below their under surfaces; and

Fig. 13 is a view similar to that of Fig. 4 but showing, on a relatively reduced scale, a modified form of fork member.

Generally speaking, the invention comprises cooperating tongue and fork members each of which has in its upper portion a hook for engaging the shoulder or equivalent contour of a flanged beam, and both of which are shaped in their lower portions to interfit and latch together, when the members are hung from the opposite sides of a beam, so that the composite hanger is secured in position around the side and bottom surfaces of the beam flanges. The lower portions of the hanger members are conveniently provided with perforations or other contours or shapes for receiving conventional fastening means, like bolts, split pins, rivets or the like, and these portions may also be provided with projections or extensions for receiving the load of the object to be hung.

In the drawings, the reference numeral 1 designates a floor slab supported by a beam 2, here shown as a conventional type of precast con-

crete joist having a central web 3 and lower side flanges 4, connected with the web by inclined shoulders 5, and having side wall 6 and an under surface 7.

This type of beam or joist is shown merely by way of illustrating the use of the invention. It forms no part of the invention, and the hanger which constitutes the invention may be used with other and different kinds of beams or joists.

The hanger includes a tongue element 8, shown in Fig. 3, and a fork member 9, shown in Fig. 4. Each of these members is preferably made of strap iron or the equivalent. Both of them are right angularly bent and have upper portions comprising hook elements for engaging the beam flange shoulders 5, and both have right-angularly inturned lower portions for interlocking with each other, as will now be explained.

The tongue member 8 is right-angularly bent in an intermediate area and angularly bent again near its upper end portion to provide the hook 10 for engaging the beam flange shoulder 5. The lower portion 11 is disposed horizontally when the intermediate portion 12 which connects it with the hook 10 is engaged with the vertical side surface 6 of the beam flange 4, and this horizontal portion 11 has securely welded or otherwise fixed to it a short cross bar 13, the ends of which project as lugs from the top surface of the portion 11. Holes 14 may be provided at one, two or three points along the portion 11.

In the form shown in Figs. 1, 2 and 4-12, the fork member, which is designated 9 in these figures, consists of a pair of principal elements, each having a hook portion 15 and an intermediate portion 16 similar to the hooks 10 and intermediate portions 12 of the tongue member 8. The fork member has two right-angularly turned lower portions 17, like the single portion 11 of the tongue member but somewhat shorter, and these are connected at their free ends by a cross bar 18 which is spot welded or otherwise secured to the portions 17 and holds them parallel and spaced apart a distance slightly greater than the width of the portion 11 of the tongue member 8, so that the two members can be interfittingly moved them from the position shown in Fig. 2 to the final position shown in Fig. 1. Holes 19 may be formed through the overlapping areas of the portions 17 and the cross bar 18.

Assuming that the angles at which the hooks 10 and 15 extend from the portions 12 and 16, respectively, are approximately the angles which the beam flange shoulders 5 make with the sides 6 of the flanges 4, and assuming that the lengths of the portions 12 and 16 are equal to the height of the sides 6, and assuming also that the sum of the distance between the inner edge of each cross member 13 and 18 and the right angle of the member is approximately equal to or only slightly greater than the width of the under surface 7 of the beam, it is a very simple matter to snap a tongue member and a fork member together to interlocking relation in a position securely engaged with the beam and with each other, by passing them through the intermediate position shown in Fig. 2 to the final relationship shown in Fig. 1.

In this final position each hook 10 and 15 is supported by a shoulder 5. The cross bar 11 has snapped behind the cross bar 18, with the two lying in the same plane, in substantially edge to edge engagement. Thus, lateral displacement or separation of the two members is prevented. The lug-like ends by which the cross bar 13 projects

from the sides of the tongue member are supported by the portions 17 of the fork member. The long end of the tongue member, with its hole or pair of holes 14, projects beyond the fork member and the beam, and all the holes with which the lower portions of the members are provided are exposed to receive bolts or other fastening elements for securing to the hanger any conduit or the like which it is customary to support from joists, a few typical examples of which are illustrated in Figs. 5-12.

Thus, Fig. 5 shows a pipe 20 fastened by a strap 21 which is connected by bolts 22 to two of the holes 14 of the tongue member so that the pipe 20 extends parallel to the beam and close to its under surface.

Fig. 6 shows a similar pipe 23 mounted transversely of a beam by a strap 24 which is bolted to the holes 19 of the fork member 9.

Fig. 7 shows a pipe 25 hung from the projecting end of the tongue member by interposing an angle element 26 between that end and a pipe clamp 27. The angle element 26 is bolted to the endmost opening 14 in the tongue member, and it may be turned and positioned to extend the pipe parallel to the beam as shown in Fig. 7, or transversely thereof, as shown in Fig. 8.

Figs. 9-12 show selected illustrative ways in which larger objects, such as sheet metal air ducts, can be mounted by the present clamp hangers.

Fig. 9 shows a duct 30 extending lengthwise through the space between a pair of adjacent joists. The duct rests at one side on the projecting ends of the tongue members of a spaced series of clamp hangers, and its opposite side edge may similarly rest on tongues projecting from a series of hangers mounted on the adjacent joist or, if the space between the joists is considerably greater than the width of the duct, the space may be bridged by a gusset bracket 31, here shown as a substantially triangular plate having two flanged sides which are secured respectively to the projecting tongue and to the duct side wall.

Connections between the duct and the hanger tongue or the gusset flange may be made by the use of self-tapping screws 32, as shown in Fig. 9.

If the duct be of different shape from that shown in Fig. 9, and/or if it be desired to position it higher in the space between adjacent joists, a bridge element like that shown at 33 in Fig. 10 may be used. This element is simply a stout strap which is right angularly bent near its end portions and inwardly flanged at its extreme ends as shown at 34 for mounting on a pair of oppositely projecting tongues, and a duct 35 is seated on the horizontally intermediate part of the bridge, to which it may if desired be secured or on which it may be left free.

Fig. 11 shows a duct 36 suspended from a pair of hangers so as to extend transversely of the joist to which these hangers are clamped. The connection is made by bolting to each of the hanger tongues the inturned ends of a strap 37 which encircles the duct.

Fig. 12 shows a large duct 38 extending parallel to a pair of joists, immediately beneath their under surfaces. The connection is made through the medium of an angle element 39 which is bridged between the joists and is bolted at 40 to the oppositely projecting tongues of clamp hangers secured to the two joists. Self-tapping screws 41 may be used to hold the duct onto the angle element.

Other uses of the device will, it is believed, be evident from a consideration of the few typical, illustrative uses which have been explained hereinabove.

Fig. 13 shows, on a relatively reduced scale, a modified form of fork member 9' in which the several parts designated by primed reference numerals are similar to the respective parts designated by corresponding unprimed reference numerals in Fig. 4. The sole difference between the two fork member embodiments is that in the Fig. 13 species the portion 17 of either or each of the tines is extended outwardly beyond the cross bar 18' and apertured near its terminal end. This provides a portion 42 projecting beyond the beam flange 4 similar to the projecting end of the tongue portion 11. It will be appreciated that when such a type of fork member is used, the composite clamp hanger provides another or additional load-carrying or connecting means, and it will be understood that this alternate type of fork member may be used with the type of tongue member which the drawings illustrate at 8 or with a tongue member in which the tine 11 terminates at the cross bar 13, or at any rate does not project beyond the beam flange.

The invention is not to be regarded as limited to the details of the illustrative embodiments, since these details may be variously modified within the scope of the invention as pointed out by the appended claims. Moreover, it is not indispensable that all features of the invention be used conjointly, since various features may be used to advantage in different combinations and subcombinations, as pointed out by the claims.

I claim:

1. A clamp hanger for attachment to a flanged beam consisting of a tongue member and a fork member both hooked over the flanges at opposite sides of the beam, the fork member having a pair of solid tines extending horizontally in one direction across the under side of the beam and the tongue member having a single solid tine extending in the opposite direction parallel to and between the fork member tines, a cross bar fixed to the fork member tines near their free ends, and a cross bar projecting laterally from the tongue tine and overlying the fork member tines to connect the members to the beam and hold them together.

2. A clamp hanger for attachment to a flanged beam consisting of a tongue member having an upper portion hooked over the flange at one side of the beam, a lower portion comprising a tine extending from said side of the beam horizontally across at least a portion of the under surface thereof, and a lug fixed to and projecting from each opposite side of said tine, and a fork member hanging from the other flange of the beam having a pair of tines wholly underlying and supporting said lugs and having a cross bar adjacent to said lugs and engageable therewith to prevent movement of any of the tines laterally of the beam toward the side thereof from which they extend.

3. A clamp hanger for attachment to a flanged beam consisting of tongue and fork members hooked over the flanges at opposite sides of the beam, the fork member having a pair of tines

extending horizontally in one direction across the under side of the beam and the tongue member having a single tine extending in the opposite direction parallel to and between the fork member tines, a cross bar fixed to the fork member tines near their free ends, and lugs projecting laterally from the tongue tine and overlying the fork member tines to connect the members to the beam and hold them together.

- 5 4. A clamp hanger as claimed in claim 3, in which the tongue member tine is longer than the fork member tines and projects outwardly beyond the edge of the flange on which the fork member is hooked.
- 10 5. A clamp hanger as claimed in claim 3, in which the tines are provided with holes to receive bolts or the like for securing conduit elements or the like to the hanger to be suspended.
- 15 6. A clamp hanger as claimed in claim 3, in which the tongue member tine is longer than the fork member tines and projects outwardly beyond the edge of the flange on which the fork member is hooked and is provided with a hole in its projecting portion to receive a bolt or the like for securing a conduit element or the like to the hanger to be suspended.
- 20 7. Means for hanging conduits and the like from a structural beam having side flanges comprising a member having at one end a hook engageable over one of the beam flanges and having at its other end a flat tongue extending forwardly across the bottom surface of the beam and provided with an opening for a bolt or the like and having lateral projections, in combination with means for holding said member in place on the beam comprising a member having at one end a pair of spaced parallel hooks engageable over the other flange of the beam and having at its other end a pair of flat tongues lying on opposite sides of the first named tongue, below said projections, and connected by a cross bar disposed behind and engaged with the projections whereby the first named tongue is supported and secured to the beam.
- 25 8. A clamp hanger as claimed in claim 2, in which at least one of said tines extend to a free end portion beyond said lugs and cross bar.
- 30 9. A clamp hanger as claimed in claim 2, in which the tine of the tongue member extends to a free end portion beyond said lugs and cross bar.
- 35 10. A clamp hanger as claimed in claim 2, in which a tine of the fork member extends to a free end portion beyond said lugs and cross bar.
- 40 11. A clamp hanger as claimed in claim 2, in which both tines of the fork member extend to free end portions beyond said lugs and cross bar.
